UNITED STATES PATENT OFFICE

FELIX SALERNO, OF NEW YORK, N. Y.

HAIR-WAVING-OPERATOR'S CABINET

Application filed July 27, 1927. Serial No. 208,724.

This invention relates to hair waving operator's cabinets.

In the art relating to waving human hair the operator uses a plurality of instruments 5 including spindles, clips, pads, strings, gauze, etc.; and in ordinary practice these instruments and articles are spread on an operating table or workstand in front of the operator where they become mixed together, misplaced 10 and oftentimes, lost.

One object of the invention is to provide a cabinet arranged to contain in handy position all of these instruments so that they may be kept in orderly arrangement, where they 15 may be reached by the operator without hesitation and which will act as a check on whether the instruments and articles have been replaced after use, that is to say, after they have been removed from the hair of the patient. 20

A further object is to provide such a cabinet which will permit the sterilization of a complete set of such instruments and articles as a whole while in the cabinet.

25 A further object is to provide such a cabinet which is easily portable while containing a complete set of instruments and articles necessary to hair waving, outside of the actual electrical instrument which supplies the heat 30 to the spindles, and which will permit sterilization while the cabinet is being carried from place to place.

The invention consists of the construction, combination and arrangement of parts, as 35 herein illustrated, described and claimed.

In the accompanying drawings, forming part hereof, is illustrated a form of embodiment of the invention, in which drawings similar reference characters designate corresponding parts, and in which:

Figure 1 is a perspective view of the cabinet in closed position;

Figure 2 is a perspective view showing the hinged top and the hinged front of the cabinet thrown back and the cabinet in position 45 ready to be used by the operator;

Figure 3 is a vertical section taken transversely of the cabinet, approximately on line 3—3 of Figure 5, looking in the direction indicated by the arrow;

Figure 4 is a vertical, transverse section taken approximately on line 4—4 of Figure 5 looking in the direction indicated by the arrow; and,

Figure 5 is a plan view of the cabinet with 55 the top removed and the front wall in closed position as shown in Figure 1.

In the hair waving art, where the instruments and articles used are brought into intimate contact with the customer, it is necessary 60 that sterilization of such instruments and articles be completely performed. Where the operator may go from one beauty shop to another it is necessary that the complete outfit of instruments and articles necessary for the 65 operation of waving be carried and it is desirable that the entire outfit be sterilized in the process of transportation.

Referring to the drawings 1 designates generally an oblong, cubic, metallic case, provided with a hinged top 2 and a hinged front wall 3. The range of movement of the front wall 3 is limited by means of flexible members 4 having their lower ends secured to the front wall and their upper ends secured to the side 70 walls of the cabinet 1. A suitable handle 5 is secured to the outside face of the hinged top 2 to render the cabinet easily portable and the common form of lock 6 is used to secure the hinged top and hinged wall together. 75

Secured on the inner face of the front wall 3 is a plurality of guides 7 arranged to receive and retain removable drawers or receptacles 8, which are used as places of deposit for the clips, pads, gauze, etc. hereinafter described. These drawers may readily be filled or partly filled with a mild antiseptic to effect the primary step of sterilization of the articles placed therein. 85

The inner face of the hinged top 2 is provided with clips 9 arranged to receive a strand of strings 10 and provided with a clip 11 arranged to receive a pile of gauze pads 12. The purpose of this arrangement is to provide a more or less resilient packing on the inner 90 face of the hinged top 2 to bear on the top of the spindle and pad retaining elements hereinafter described.

Disposed inside of the cabinet 1 in spaced relation to each other are vertical partitions 100

13, so spaced as to leave an area which may be filled with sachet tubes.

The vertical partitions on the front face thereof are provided with rounded walls 14 having front slots 15 arranged to receive pads 16. The pads in one receptacle so formed may be the ordinary rubber pads for insulation purposes and in the adjacent receptacle the felt pads which are disposed on the curling spindles adjacent the rubber pads. The arrangement described readily segregates the pads into classes and maintains them segregated.

Retained between the walls 13 and the end 15 and rear walls of the cabinet 1 is a plurality of removable receptacles 17 provided with openings 18 in the upper wall thereof adapted to receive a plurality of curling spindles 19. The number of spindles may be proportioned 20 to the ordinary number required for waving a particular head of hair. The receptacles 17 are provided adjacent their lower ends with openings 20 (see Figure 3) to permit the passage of a gaseous disinfectant such as formaldehyde so that the curling spindles being more or less conical in shape and being maintained in a vertical position, drain downwards and are thoroughly disinfected by such a disinfectant.

30 Disposed across the space formed by the spaced walls 17, adjacent its lower end, is a horizontal partition 21, beneath which is disposed a drawer 22 designed to receive the clips which are used in connection with the 35 step of retaining the hair on the curling spindles, which drawer may readily be perforated to permit the passage of a gaseous or vaporous disinfectant. A suitable handle 23 is secured to the front of the drawer 22. Beneath the rounded walls 14 suitable spaces 40 24 are left adapted to receive other articles or cups of a vaporizing disinfectant.

The horizontal partition 21 together with the walls 13 form a receptacle adapted to receive a supply of sachet tubes (see Figures 4 and 5) 25 which are used in the art of hair waving, which require no disinfecting and which should be readily removable.

Having thus fully described the invention 50 what is claimed as new and desired to be secured by Letters Patent is:

1. In a device of the character described in combination with a cabinet having a hinged top and a hinged vertical wall, retaining clips 55 on the inside face of the top, a plurality of perforate spindle receptacles, and means for retaining and segregating pads.

2. In a device of the character described in combination with a cabinet having a hinged 60 top and a hinged vertical wall, removable trays on the inside face of the hinged wall, a plurality of perforate spindle receptacles and means for retaining and segregating pads.

3. In a device of the character described in 65 combination with a cabinet having a hinged

top and a hinged vertical wall, means for limiting the movement of the hinged wall with relation to the body of the cabinet, a plurality of perforate spindle receptacles, and means for retaining and segregating pads.

4. In a device of the character described in combination with a cabinet having a hinged top and a hinged vertical wall, partitions spaced apart and formed into pad receptacles and a drawer disposed intermediate of the partitions.

5. In a device of the character described, in combination with a cabinet having a hinged top and a hinged vertical wall, partitions spaced apart and formed into pad receptacles, a horizontal partition connecting the walls and a drawer disposed between the spaced walls and beneath the horizontal partition, arranged to leave a recess above the horizontal partition between the spaced walls.

6. In a device of the character described in combination with a cabinet having a hinged top and a vertical wall, partitions spaced apart and formed into pad receptacles, a drawer disposed intermediate of the partition and a plurality of perforate spindle receiving elements disposed behind the partition.

7. In a device of the character described a unitary construction comprising a cabinet having a hinged top and one hinged wall; 95 removable trays carried by the wall; retaining clips on the top; spaced partitions disposed in the cabinet and formed to receive pads and to leave a space between the partitions; a drawer disposed below this space; 100 and, a plurality of removable, perforate receptacles arranged to receive and maintain in vertical position a plurality of spindles.

8. In a device of the character described in combination with a cabinet, a plurality of perforate receptacles arranged to receive spindles and to leave a space beneath the bottom thereof disposed in the cabinet and means for retaining and segregating pads of different characteristics arranged in front of the receptacles in the cabinet.

Signed at New York, in the county of New York and State of New York, this 22nd day of July A. D. 1927.
